UNITED STATES PATENT OFFICE.

EDWARD W. BURGESS, OF CHICAGO, ILLINOIS, ASSIGNEE, BY MESNE ASSIGNMENTS, TO
INTERNATIONAL HARVESTER COMPANY, A CORPORATION OF NEW JERSEY.

SAND-CUTTING MACHINE.

1,330,057.

Specification of Letters Patent. Patented Feb. 10, 1920.

Application filed December 23, 1916. Serial No. 138,635.

To all whom it may concern:

Be it known that I, EDWARD W. BURGESS, a citizen of the United States, residing at Chicago, in the county of Cook and State 5 of Illinois, have invented certain new and useful Improvements in Sand-Cutting Machines, of which the following is a full, clear, and exact specification.

My invention relates to sand cutting machines for foundry use adapted to be propelled over sand distributed upon the foundry floor, and to cut and shovel it rearward, upward and in converging lines in a manner to form a ridge having downwardly 15 sloping sides in rear of the machine as it is constantly advanced.

The object of my invention is to provide a machine for the purpose indicated that will be simple and strong in its construction 20 and efficient in operation.

I attain this object by means of the mechanism illustrated in the accompanying drawings, in which—

Figure 1 is a top plan view of a sand 25 cutting machine embodying my invention;

Fig. 2 is a side elevation of Fig. 1;

Fig. 3 is a plan view on an enlarged scale of part of the shovel carrying cylinder as shown in Fig. 1.

Fig. 4 is a side elevational view on an enlarged scale of the sand mixing shovels and the operating connections therefor, and

Fig. 5 is a plan view on an enlarged scale of the tilting means for the sand cutting 35 frame.

The same reference characters designate like parts throughout the several views.

A wheel supported frame includes side frame members having horizontally disposed 40 portions 1 extending in a fore and aft direction upon opposite sides of the machine, having vertically disposed portions 2 at their front ends that terminate in forwardly extending horizontally disposed portions 3, 45 to which is secured a transversely disposed frame member 4, preferably having a channel section, and 5 represents truss members connecting opposite ends of the portions 1 with opposite ends of the portions 3. 50 Secured to the front ends of the parts 1 are

hangers 6, having sleeve members 7 that receive a fixed axle 8 having carrying wheels 9 journaled upon its opposite ends. 10 represents hangers secured to the rear ends of the parts 1 and receiving self-aligning bearing sleeves 11, in which is journaled a transverse cylinder shaft 12. Secured to the shaft at opposite sides of the machine are spider members 13, and 14 represents a supplemental spider member secured to the middle 55 thereof. Secured to the free ends of the radially disposed arms of the spiders are a series of tubular shovel carrying bars 15, and means for mounting the shovels thereon include bracket members 16 secured to the 60 bars, preferably four, spaced apart upon each bar. The brackets include sleeve members 17 disposed parallel with the arms of the spiders and having journaled therein rock shafts 18, having secured to their inner 65 ends lever arms 19 19' and to their opposite ends shank members 20 by means of removable pins 21, to which are secured radially disposed shovel blades 22. The shafts 18, therefore, form the longitudinal pivots or 70 axes of the shovels. In order that the sand thrown laterally from the shovels disposed remote from the longitudinal center of the machine, or at the outer edge portions of the machine, may be deposited in the same 75 ridge on which the sand thrown by the shovels located near the longitudinal center of the machine, is deposited, the lever arms 19 of the outer shovels are made shorter than the arms 19' of the centrally disposed 80 shovels, whereby the shovels operated through arms 19 will be turned through a greater angle than those operated from the arms 19'. This construction is clearly illustrated in Fig. 3. The arms of the spider 85 members 13, adjacent the bars 15, are provided with angular openings disposed parallel with said bars and adapted to slidably receive controlling links 23, having their inner ends pivotally connected, by 90 means of links 24, with adjacent arms 19 carried by the rock shafts 18, and 25 represents a link connection between said pair of arms upon opposite sides of the spider member 14. Secured to opposite ends of the con- 95 100

- trolling links 23 are inwardly extending radially disposed studs 26, upon which are journaled rollers 27 adapted to travel in peripheral cam members 28 mounted axially at opposite sides of the machine and provided with ear members 29 having concentric slots 30 therein whereby the cam members are adjustably secured to the parts 1 of the wheel frame by means of a bolt 31.
- 10 Mounted upon the transverse frame member 4 is a motor 32 including a power shaft 33, to which is secured a pinion 34 meshing with a speed reducing gear 35 journaled upon a stud 36, and having integral therewith a sprocket wheel 37 that is operatively connected by means of a sprocket chain 38 with a driven sprocket 39 secured to the cylinder shaft 12, preferably by means of a break pin 40.
- 15 20 In operation, when the machine is advancing, the shovel carrying cylinder is rotated in the same direction as the carrying wheels, and the shovels enter the sand on lines parallel with the axis of the cylinder shaft 12 and carry their loads upward and rearward.
- 25 The peripheral cam members 28 are provided with laterally disposed wave portions 41 that engage the rollers 27 in a manner to reciprocate the links 24 in opposite directions in a manner to turn the shovels axially when they have reached a predetermined point of rotation with the cylinder and thereby cause them to throw their loads upward, rearward and inward in a manner to leave the sand in a narrow ridge behind the machine and having substantially the same contour as in the old practice of hand shoveling.
- 30 35 The cam members 28 are adjustable axially for the purpose of regulating the point of discharge of the load from the shovels, and the degree of rocking movement axially of the shovels is determined by the relative lengths of the arms 19 and the throw of the wave portions 41 of the cam members 28.
- 40 45 50 Means are provided for propelling the machine backward or forward comprising a tractor 42, including a frame member 43, upon which is mounted a motor 44, including speed changing and forward and reverse gearing 45 whereby it is operatively connected with a single traction wheel 46 by means of driving and driven sprocket wheels 47 and 48, respectively, and a sprocket chain 49. 55 50 represents depending frame members upon opposite sides of the frame member 43, that are reinforced by means of brace members 51, and carrying at their lower ends an axle member 52, upon which the traction wheel 46 is journaled.
- 60 65 Integral with the frame member 43 is a vertically disposed tubular member 53, in which is journaled a coupling pin 54 whereby the frame is flexibly connected with the front end of a draft frame 55, including upper and lower bars 56 and 57, respectively, that extend rearward and converging at their rear ends are secured to a bracket member 58 mounted upon the end of the axle 8 adjacent the hub of the carrying wheel 9. 59 70 75 80 85 90 95 100 105 110 115 120 125 130 represents a supplemental draft frame member having its front end secured to the member 57 and inclined inward, rearward and downward, the rear end portion being substantially horizontal and being secured to a bracket member 60 mounted upon the axle 8 adjacent the inner end of the sleeve member 7 of the hanger 6.
- Secured to the tubular member 53 is a steering worm wheel 61 that is controlled by means including a worm 62 journaled in a bracket member 63 secured to the draft frame member 56 and provided with a sprocket wheel 64 whereby it is operatively connected, by means of a sprocket chain 65, with a second sprocket wheel 66 carried by a shaft 67 85 90 95 100 105 110 115 120 125 130 journaled at the upper end of a standard 68 secured to the draft frame member 56 and provided with a crank 69 convenient to the hand of an operator from the seat 70.
- The shovel controlling elements are protected by means of dust excluding segmental plates 71 secured to the tubular shovel carrying bars 15. In Figs. 1 and 3 the plates on the front of the machine are not shown in order to show the lever mechanism and links. 95 The plates when in place overlap as shown in Fig. 2 and form a cylindrical casing which entirely incloses the lever and link connections for the shovels. Means are provided for rocking the cylinder carrying frame about the axis of the carrying wheels 9 for the purpose of raising or lowering the cylinder, said means including a segmental rack 72 concentric with the axle 8 and secured to the vertical portion 2 of the side member of the wheel frame, a worm 73 engaging with the rack and controlled by means of a vertically disposed shaft 74 journaled in a bearing bracket 75 carried by the draft frame member 59, the upper end of the shaft being 110 provided with a crank 76 whereby it may be manipulated. The segmental rack 72 is provided with a stop member 77 adapted to engage with the bearing bracket 75 in a manner to limit a downward movement of the 115 cylinder.
- In operation the machine is drawn forward upon the floor of the foundry and over the sand to be cut. The shovels are given a constant rotative speed about the axis of the shaft 12 and the different series enter the sand on lines parallel with the axis of the shaft and are in line with each other. When the shovels are picking up a load there is no inward packing action upon the sand, and it is carried rearward in a loose condition. When the shovels are turned about the axes of the rock shafts 18, the sand is thrown from the blades inward and upward and is formed into a symmetrical ridge and is left 130.

in a desirable tempered and friable condition.

Having shown and described one form which my invention may assume in practice, I do not desire that it be confined to the specific details of the structure as illustrated, it being understood that changes may be made in the form, proportion and organization of its several parts without departing from the spirit of the invention as indicated in the appended claims.

What I claim as my invention, and desire to secure by Letters Patent, is:

1. A sand cutting machine including, in combination, a plurality of sand engaging elements mounted to move together through a mass of sand, and means for positively rocking said elements axially in opposite directions while a load is being discharged therefrom, certain of said elements being rocked in one direction as certain others of said elements are rocked in the opposite direction.

2. A sand cutting machine including, in combination, a plurality of sand engaging elements having individual mountings and adapted to move together through a mass of sand, and means for positively rocking said elements axially in opposite directions while a load is being discharged therefrom, certain of said elements being rocked through different angles of movement from certain others of said elements.

3. A sand cutting machine including, in combination, a rotatable cylinder, a plurality of series of shovel blades carried thereby and turnable about radial axes, the blades of each series being normally disposed in lines parallel with the axis of said cylinder, and means for rocking said blades axially in opposite directions while a load is being discharged therefrom, certain of the blades of each series being rocked in one direction as certain other blades of the same series are rocked in the opposite direction.

4. A sand cutting machine including in combination, a plurality of sand cutting elements mounted on longitudinal pivots, and means for moving said elements bodily through a mass of sand and for positively rotating certain of said elements on their pivots, certain of said elements being rotated in one direction as certain others of said elements are rotated in the opposite direction.

5. A sand cutting machine including, in combination, a plurality of sand cutting elements disposed across said machine and laterally spaced from each other, and means for rocking the elements disposed adjacent the longitudinal center of the machine through a lesser angle of movement than those elements disposed more remote from said longitudinal center.

6. A sand cutting machine including, in combination, a plurality of sand cutting ele-

ments disposed across the said machine and laterally spaced from each other, and means including lever arms of different lengths for rocking the elements disposed adjacent the longitudinal center of the machine through a lesser angle than those disposed more remote from said longitudinal center.

7. A sand cutting machine including in combination, a plurality of sets of sand cutting elements, means for moving said elements bodily through a mass of sand, and means for positively rocking said sets of elements in directions transverse to the path of movement of said elements, certain elements of each set being rocked in one direction as certain other elements of said set are rocked in the opposite direction.

8. A sand cutting machine including in combination, a plurality of sand cutting elements adapted to be carried through a mass of sand, and to turn about radially disposed axes, and means for positively rocking said elements axially in opposite directions and in such a manner as to deposit the sand in a single ridge adjacent the longitudinal center of the machine.

9. A sand cutting machine including in combination, a plurality of individually mounted sand cutting and elevating elements adapted to be rotatably carried through a mass of sand and to turn about radially disposed axes, and means for positively rocking said elements axially, certain of said elements being rocked in one direction as certain others of said elements are rocked in the opposite direction.

10. A sand cutting machine including in combination, a plurality of sets of individually mounted sand cutting and elevating elements, adapted to be rotatably carried through a mass of sand and to turn about radially disposed axes, and means for positively rocking said elements axially in opposite directions at a predetermined point in the rotative movement thereof, the elements of each set being rocked in such directions that they will deposit the sand in a single ridge.

11. A sand cutting machine including in combination, a plurality of sand cutting and elevating elements adapted to be rotatably carried through a mass of sand and to turn about radially disposed axes, means for positively rocking said elements axially in opposite directions, and means for adjusting said rocking means to regulate the point in the rotative movement thereof at which said elements are rocked on their axes.

12. A sand cutting machine including in combination, a plurality of individually mounted sand cutting and elevating elements adapted to be rotatably carried through a mass of sand and to turn about radially disposed axes, a cam member operatively connected with said elements for posi-

tively rocking them in opposite directions, and means connecting said elements to said cam member in such a manner that certain elements will be rocked through different angles from certain others of said elements.

13. A sand cutting machine including in combination, a plurality of individually mounted sand cutting and elevating elements adapted to be rotatably carried through a mass of sand and to turn about radially disposed axes, a cam member concentrically disposed relative to the axis of rotation of said sand cutting elements, operative connections between said cam member and said cutting elements whereby said elements are positively rocked in opposite directions during their rotative movement, said connections operating to rock certain of said elements through lesser angles of movement than certain others of said elements.

14. A sand cutting machine including in combination, a plurality of individually mounted sand cutting and elevating elements adapted to be rotatably carried through a mass of sand and to turn about radially disposed axes, a cam member concentrically disposed relative to the axis of rotation of said sand cutting elements, operative connections between said cam member and said cutting elements, and means for adjusting said cam on its axis to regulate the action thereof relative to said cutting elements.

15. A sand cutting machine including in combination, a plurality of laterally separated individually mounted sand cutting and elevating elements adapted to be rotatably carried through a mass of sand and to turn about axes radially disposed relative to the axis of rotation of said cutting elements, and means for rocking said elements axially, certain of said laterally separated elements being rocked in one direction and others of said elements being rocked in the opposite direction.

16. A sand cutting machine including in combination, a plurality of laterally separated individually mounted sand cutting and elevating elements, adapted to be rotatably carried through a mass of sand and to turn about axes radially disposed relative to the axis of rotation of said cutting elements, and means for rocking said elements axially at a predetermined point in the rotative movement thereof, certain of said laterally spaced elements being rotated through a lesser angle than certain others thereof.

17. A sand cutting machine including in combination, a plurality of laterally separated individually mounted sand cutting and elevating elements, adapted to be rotatably carried through a mass of sand and to turn about axes radially disposed relative to the axis of rotation of said cutting ele-

ments, and means for rocking said elements through different angles of movement axially during the rotative movement thereof.

18. A sand cutting machine including in combination, a plurality of sand cutting and elevating elements, means for moving said elements bodily through a mass of sand, and means for turning said elements on their longitudinal axes during the bodily movement thereof, certain elements being rotated through different angles from certain other elements.

19. A sand cutting machine including in combination, a plurality of laterally separated and individually mounted sand cutting and elevating elements, adapted to be rotatably carried through a mass of sand and to turn about axes radially disposed relative to the axis of rotation of said cutting elements, and means for rocking said elements axially in opposite directions during the rotative movement thereof, said means operating to rock the elements near the longitudinal center of the machine through a lesser angle than those located more remote therefrom.

20. A sand cutting machine including in combination, a plurality of laterally separated, individually mounted, longitudinally aligned sand cutting and elevating elements, adapted to be rotatably carried through a mass of sand and to turn about axes radially disposed relative to the axis of rotation, and means for rocking said elements axially during the rotative movement thereof.

21. A sand cutting machine including in combination, a rotatable cylinder, a plurality of sand engaging and elevating elements disposed in separate longitudinal lines spaced apart peripherally upon said cylinder and individually turnable about radially disposed axes, controlling elements carried by said cylinder, and operative connections between said controlling elements and said elevating elements whereby elevating elements in each longitudinal line are turned axially in opposite directions at a predetermined point in the rotation of said cylinder.

22. A sand cutting machine including in combination, a rotatable cylinder, sand cutting elements disposed in separate longitudinal lines spaced apart upon the periphery of said cylinder, and means for rotating elements in each longitudinal line in opposite directions during the rotation of said cylinder.

23. A sand cutting machine including, in combination, a rotatable cylinder, a plurality of series of shovel blades carried thereby, the blades of each series being normally disposed in lines parallel with the axis of said cylinder, and means for rocking said blades axially while a load is being discharged therefrom, said means being operable to rock the blades of each series from

- opposite ends of said cylinder toward its middle in opposite directions.
24. A sand cutting machine including, in combination, a rotatable cylinder, a plurality of series of shovel blades carried thereby by the blades of each series being normally disposed in lines parallel with the axis of said cylinder and turnable on radially disposed axes, means for rocking said blades axially while a load is being discharged therefrom, and means for adjusting said rocking means in a manner to regulate the point of discharge of the load.
25. A sand cutting machine including, in combination, a wheel supported frame, a cutting cylinder journaled upon said frame, said cylinder including a shaft, spiders secured to said shaft, bars secured to the arms of said spiders, shovels carried by said bars, cams secured to said frame, and operative connections between said cams and said shovels whereby said shovels are rocked axially when said cylinder is rotated.
26. A sand cutting machine including, in combination, a wheel supported frame, a cutting cylinder journaled upon said frame, said cylinder including a shaft, spiders secured to said shaft, bars secured to the arms of said spiders, a plurality of shovels carried by each of said bars, cams secured to said frame at opposite ends of said cylinder, and operative connections between said cams and shovels whereby said shovels are rocked axially in a direction to throw the sand inward, forward and rearward from opposite sides of the machine.
27. A sand cutting machine including, in combination, a wheel supported frame, a cutting cylinder journaled upon said frame, said cylinder including a shaft, spiders secured to said shaft, bars secured to the arms of said spiders, two groups of shovels carried by each of said bars, said groups being disposed upon opposite sides of the middle of said cylinder, cams secured to said frame at opposite ends of said cylinder, and operative connections between said cams and the separate groups of shovels whereby the shovels of opposing groups carried by the same bar are rocked axially in opposite directions when the cylinder is rotated.
28. A sand cutting machine including, in combination, a wheel supported frame, a cutting cylinder journaled upon said frame, said cylinder including a shaft, spiders secured to said shaft, bars secured to the arms of said spiders, two groups of shovels carried by each of said bars, said groups being disposed upon opposite sides of the middle of said cylinder, cams secured to said frame at opposite ends of said cylinder, and operative connections between said cams and the separate groups of shovels whereby the shovels of opposing groups carried by the same bars are rocked axially and through different angles in opposite directions when said cylinder is rotated.
29. A sand cutting machine including, in combination, a wheel supported frame, a cutting cylinder journaled upon said frame, said cylinder including a shaft, spiders secured to opposite ends of said shaft, bars secured to the arms of said spiders, a plurality of brackets secured to each of said bars, radially disposed rock shafts journaled in said brackets, shovels carried by said rock shafts and normally disposed parallel with the axis of said cylinder, cams secured to said frame at opposite ends of said cylinder, arms secured to said rock shafts, and links slidably mounted upon the arms of said spiders having one end thereof engaging with said cams and their opposite ends operatively connected with the arms secured to said rock shafts.
30. A sand cutting machine including, in combination, a wheel supported frame, a cutting cylinder journaled upon said frame, said cylinder including a shaft, spiders secured to opposite ends of said shaft, bars secured to the arms of said spiders, a plurality of brackets secured to each of said bars, radially disposed rock shafts journaled in said brackets, shovels carried by said rock shafts and normally disposed parallel with the axis of said cylinder, cams secured to said frame at opposite ends of said cylinder, arms secured to said rock shafts, said arms having different lengths, and links slidably mounted upon the arms of said spiders having one end thereof engaging with said cams and their opposite ends connected by means of links with the arms secured to said rock shafts.
31. A sand cutting machine including in combination, an axle, wheels carried by said axle, a frame mounted intermediate its ends on said axle, sand cutting mechanism carried by said frame at one side of said axle, a source of power for operating said cutting mechanism carried by said frame at the opposite side of said axle, a separate frame having propelling means thereon connected to said axle and means disposed on said last-named frame at one side of said axle and operatively connected with said frame for raising and lowering said sand cutting mechanism.
32. A sand cutting machine including, in combination, a frame, carrying wheels having said frame mounted intermediate its ends thereon, a cutting cylinder journaled upon the rear end of said frame, machine propelling means including a draft element, and means co-operating with said draft element for rocking said frame about the axis of said carrying wheels to raise or lower said cylinder.
33. A sand cutting machine including, in combination, a frame, carrying wheels hav-

ing said frame mounted intermediate its ends thereon, a cutting cylinder journaled upon the rear end of said frame, machine propelling means including a draft element, 5 means coöperating with said draft element for rocking said frame about the axis of said carrying wheels to raise or lower said cylinder, said means including a segmental rack carried by said frame, and a worm jour- 10 naled upon said draft element and engaging with said rack.

34. A sand cutting machine including, in combination, a frame, carrying wheels having said frame mounted thereon, a cutting cylinder journaled upon said frame, machine propelling means including a draft element, means coöperating with said draft element for rocking said frame about the axis of said carrying wheels to raise or lower 15 said cylinder, said means including a segmental rack carried by said frame, a worm journaled upon said draft element and engaging with said rack, and a stop member carried by said rack and adapted to engage 20 with a fixed part of said draft element in a manner to limit a downward movement of said cylinder.

35. A sand cutting machine including, in combination, a frame, a cutting cylinder 30 journaled upon said frame, said cylinder including an axle, spiders secured to said axle, bars secured to the free ends of the arms of said spiders, shovels mounted upon said bars, and segmental dust excluding plates se- 35 cured to said bars.

36. A sand cutting machine including in

combination, a wheel supported frame, a rotatable cylinder mounted upon said frame, a plurality of sand engaging and elevating elements mounted in groups disposed in separate longitudinal lines spaced apart peripherally upon said cylinder and individually turnable about radially disposed axes, controlling elements carried by said frame, operative connections between said controlling elements and said elevating elements, whereby said elevating elements are turned axially inward from opposite ends of and toward the middle of said cylinder at a predetermined point in the rotation of said cylinder, and means for adjusting said controlling elements in a manner to vary the point at which an axial turning movement is imparted to said elevating elements in the rotation of said cylinder.

37. A sand cutting machine including in combination, a rotatable cylinder, a plurality of sand engaging and elevating elements mounted in groups disposed in separate longitudinal lines spaced apart peripherally upon said cylinder, and individually turnable about radially disposed axes, cams secured to opposite sides of said frame concentric with the axis of said cylinder, operative connections between said cams and said elevating elements whereby the latter are turned axially at a predetermined point in the rotation of said cylinder, and means for adjusting said cams axially relative to said cylinder.

In testimony whereof I affix my signature.

EDWARD W. BURGESS.
